UNITED STATES PATENT OFFICE

JOHN D. MCCLINTOCK, OF PHILADELPHIA, PENNSYLVANIA, ASSIGNOR TO WILLIAM SELLERS & COMPANY, INCORPORATED, OF PHILADELPHIA, PENNSYLVANIA, A CORPORATION OF PENNSYLVANIA

INJECTOR

Application filed March 1, 1930. Serial No. 432,527.

My invention relates to an improvement in injectors and more particularly to improved means for indicating failure of an injector to function.

As is well known, injectors, after having been properly started, may fail to continue to function properly, or cease to function, from a variety of causes, as, for example, from a cessation of the supply of steam or water, failure to maintain the relative proportions of steam and water within the range of maximum and minimum capacities of the injector, etc. Such abnormal conditions effect the efficient operation of the injector variously, as by causing wastage of water, blowing back of steam through the water supply, etc., or cause it to cease to function, and require immediate correction.

The failure of an injector may be ordinarily readily observed where the injector is placed in an observable position, as in a stationary plant, but such is not the case, more particularly, on a locomotive where due to restricted space the injector is installed outside of the cab and is non-observable by either the engineer or the fireman, who ordinarily can only determine failure of the injector from observation of the fact that the boiler is not receiving water.

Heretofore various means have been suggested for indicating failure of an injector at a remote point, as in the cab of a locomotive and such means have involved in one case the provision of a pipe leading from the injector through which steam is discharged to attract an operator's attention when the injector ceases to function properly and in another case, as disclosed in U. S. Letters Patent No. 1,318,089, dated October 7, 1919, the provision of an indicator so arranged as to be hidden under the influence of vacuum in the injector when it is functioning normally and to appear on breaking of the vacuum on failure of the injector. Such means have, however, not proved entirely satisfactory in the one case due to failure to observe the telltale and in the other due to the unpleasant effect of the escaping steam.

Now, it is the object of my invention to provide improved means for indicating fail-

ure of an injector, of such character as to indicate at a point remote from the injector, as in the cab of a locomotive, and so constructed as to indicate normal efficient operation and failure of an injector in a definite and readily observable manner.

Having indicated in a general way the nature and purpose of my invention, I will proceed to a more detailed description thereof with reference to the accompanying drawing in which I have illustrated a preferred embodiment and in which the single figure is a sectional view of an injector with associated indicating means embodying my invention.

In the drawing *a* indicates the casing of an injector of usual construction and within which is a combining tube *b*, a steam nozzle *c* and a delivery tube *d*. *e* indicates a steam inlet suitably controlled by a valve and which communicates with the steam nozzle *e*, while *f* indicates a water inlet suitably controlled by a valve, not shown, and *g* indicates the outlet from the injector to the boiler. The combining tube *b* is provided with an overflow *h* which communicates with a chamber *i* provided with an outlet *j* which communicates with a waste pipe, there being a valve, not shown, between outlet *j* and the waste pipe, as shown, for example, in United States Patent No. 1,318,089.

Connected to the overflow chamber *i* of the injector is a pipe *k* which leads to a casing *m*, desirably positioned in the cab of a locomotive, or other position remote from the injector. Within the casing *m* is an apertured seat *n* beneath which is formed a cylinder *o* within which is positioned a piston *p*. The lower end of the cylinder *o* is closed by means of a screw plug having a central bore through which extends a stem *q* secured to piston *p*. A conduit *r* in the casing *m* connects cylinder *o* with an outlet *s*, discharge through the conduit being controlled by a ball check *t*.

In the operation of the device embodying my invention, for example, as described above, it will be understood that when the injector is operating efficiently, the overflow chamber *i* will be under partial vacuum in

the chamber *i*, which will be communicated through pipe *k* to cylinder *o* in the casing *m*, causing piston *p* to be lifted up against the seat *u* with withdrawal of the stem *q* from its extension through the plug closing the open end of the cylinder. The conduit *r*, under such condition, will be closed by the ball check *t* and further protected by the piston when in position against the seat *n*. So long as the injector continues to operate efficiently, the stem *q* will be withdrawn from the seat under the influence of the vacuum in chamber *i* as communicated to cylinder *o* as described. Should the normal operation of the injector be interrupted, for example, by the cessation of the supply of water or steam, the partial vacuum in chamber *i* will be lost and chamber *i* will receive steam under pressure from the overflow chamber *x* of the combining tube. On loss of the partial vacuum in overflow chamber *i*, the partial vacuum in cylinder *o* will be lost and the piston *p* will drop in cylinder *o* of its own weight, or under the influence of steam pressure, causing stem *q* to be extended through the plug closing the open end of the cylinder. The stem *q*, which is desirably painted red and which, as has been indicated, is hidden during efficient operation of the injector will, on loss of the partial vacuum, come into view and act as a signal of the fact that the injector has ceased to operate. Steam, when discharged into overflow chamber *i*, passes through pipe *k* and into cylinder *o*, from which it passes through the outlet *s*, raising the ball check *t* in its passage. The outlet *s* is desirably connected to discharge into the atmosphere at a point where it may be observed by an operator, and where the device is positioned in a locomotive cab, it may, for example, discharge just above the funnel positioned to receive discharge from the boiler test cocks.

It will now be observed that the device embodying my invention provides a dual indication of the efficient and inefficient operation of the injector. Where the injector is operating efficiently, the stem *q* of the indicator is withdrawn from the seat and there is no steam discharged from the outlet *s*. However, when the injector ceases to operate the stem *q* is immediately projected into view and steam is discharged from the outlet *s*. In the device embodying my invention the ball check *t* and the piston *p* seated against the seat *n* serve to positively prevent inflow of air through outlet *s* to the detriment of the partial vacuum in overflow chamber *i*. It will be understood that the embodiment of my invention described may be variously modified within the scope of my invention. It will be further understood that the device in accordance with my invention may be used in association with any form of injector, the

particular form described being by way of illustration only.

What I claim and desire to protect by Letters Patent is:

1. In combination, an injector including an overflow chamber normally under partial vacuum when the injector is functioning correctly and adapted to receive steam under pressure when the injector ceases to function correctly, an indicator operable under the influence of relative pressure in the overflow chamber, and means associated with the indicator for permitting the escape of steam when the overflow chamber is under steam pressure within the overflow chamber. 70 75 80

2. In combination, an injector including an overflow chamber normally under partial vacuum when the injector is functioning correctly and adapted to receive steam under pressure when the injector ceases to function correctly, an indicator operable by relative pressure within said overflow chamber and means associated with said indicator for permitting the escape of steam when said overflow is under steam pressure, said means being arranged to prevent the communication of atmospheric pressure to said overflow chamber. 85 90 95

3. In combination, an injector including an overflow chamber normally under partial vacuum when the injector is functioning correctly and adapted to receive steam under pressure when the injector ceases to function correctly, a cylinder, a conduit affording communication between said chamber and said cylinder, a piston in said cylinder, a stem carried by said piston, said piston being adapted to be positioned under the influence of pressure to extend said stem without said cylinder and adapted to be positioned under the influence of partial vacuum within said overflow chamber to withdraw said stem within the cylinder, a conduit affording an outlet from said cylinder and a check valve in said conduit arranged to permit discharge of steam from the cylinder. 100 105 110

In testimony of which invention, I have hereunto set my hand, at Philadelphia, Pennsylvania, on this 25th day of February, 1930.

JOHN D. McCLINTOCK. 115 120
